[57] ABSTRACT

A davit for use in lowering and raising life crafts such as life boats and survival capsules with respect to

decking upon which the davit is supported. The davit comprises a fixed hollow beam which slidably receives a travelling boom which, in turn, houses a dump-hook assembly. The latter is capable of movement along the travelling boom. A cable extends from a power source through the davit and over the dump-hook to suspend the life craft beneath the davit. The fixed beam is canted so that its outboard end extends downwardly at an angle which permits outboard-directed movement, under the influence of gravity, of the travelling boom and dump-lock assembly once the holding brake or mechanism is released. Retraction of the dump-hook assembly and travelling boom into the fixed beam is provided by the powered cable.

The outboard-directed movements of the travelling boom and dump-hook assembly are coordinated so that termination of such movement of the travelling boom initiates the outboard-directed movement of the dump-hook assembly. The inboard-directed movements of these components are coordinated in a similar but in reverse manner. A cut-out is provided in the top of the outboard end of the travelling boom which cooperates with certain stops to limit the outboard movement of the dump-hook assembly and to cause it to rotate about a transverse axis to permit lowering of the life craft. The davit also includes components which ensure that the dump-hook assembly is retracted before the travelling boom commences to retract into the fixed beam.

TELESCOPING GRAVITY DAVIT

BACKGROUND OF THE INVENTION

This invention relates to life craft handling and, more particularly, to a canted telescoping davit which is extensible by gravity.

Davits have long been in use on ships and artificial islands, e.g., off-shore oil drilling rigs, as evidenced by U.S. Pat. No. 646,181 issued Mar. 27, 1900. Although most of the davits, until recently, have been mechanical davits which employ a power source to produce outboard (as well as inboard) movement of the life craft, the current trend is toward employment of gravity davits, particularly for larger life crafts, which are canted to use gravity to produce outboard movement of the life craft. Inboard movement of a life craft on a gravity davit is similar to that on a mechanical davit.

The reason for the present preference for gravity davits over mechanical davits is that functioning of the gravity davits, especially when a life craft is to be lowered into water, is much more predictable and reliable.

Gravity davits have been patented as evidenced by U.S. Pat. Nos. 2,929,081 and 2,949,617, issued on Mar. 22, 1960 and Aug. 28, 1960 to H.G. Taylor. A disadvantage of the gravity davit described in these patents is that the life craft remains suspended at the outboard end of the travelling davit arm rather than being drawn inboard along at least a portion of the latter's length. This means that the life craft is not drawn inboard as far as it can be for more compact storage and to minimize torque loading resulting from suspension of the life craft. It also means that maximum torque loading is always applied to the travelling davit arm which thereby subjects the latter and the stationary tracks to substantial bending stresses.

SUMMARY OF THE INVENTION

This invention is embodied in a telescoping gravity davit which comprises a hollow beam which is canted downward in an outboard direction and which is mounted in a fixed position above a deck with respect to which a life craft is to be lowered or raised. The fixed beam slidably receives a travelling boom which, in turn, houses a dump-book assembly which has limited travel within the travelling boom. A cable extends from a power source through the davit and over the dump-book for connection to a life craft which is stored immediately under the fixed beam.

An actuator is provided on the travelling boom which is connected to a retaining mechanism mounted in the travelling boom which normally restrains the dump-book assembly from movement relative to the travelling boom. The actuator cooperates with a stop mounted within the fixed beam to initiate outboard movement of the dump-book assembly simultaneously with termination of the outboard movement of the travelling boom. It also cooperates with this stop to lock the dump-book assembly into the retaining mechanism at the end of the inboard movement of the dump-book assembly at the same time as the travelling boom commences its inboard movement.

A cut-out is also provided in the outboard end of the travelling boom to cooperate with stops located in that end of the boom to both terminate the outboard movement of the dump-book assembly and to cause it to rotate about a transverse axis to release the life craft for descent into the water.

A major advantage of the herein-described structure is that it occupies a minimum of space since the dump-book assembly, below which the life craft is suspended, retracts into the fixed beam. Additionally, the life craft in its stored position is located relatively close to the inboard end of the fixed beam to minimize severe loads during storage in severe environments.

DESCRIPTION OF THE DRAWINGS

FIG. 1 is a side elevation view of the herein-described gravity davit supported above a deck and supporting a survival capsule;

FIG. 2 is a side elevational view of the gravity davit of FIG. 1 showing it in its stowed condition.

FIG. 3 is a side elevational view of the gravity davit of FIG. 1 showing the travelling boom in its outboard position.

FIG. 4 is a top plan view of the gravity davit of FIG. 1 showing the dump-book assembly and travelling boom in their outboard positions.

FIG. 5 is an end elevational view of the gravity davit taken along the line 5-5 of FIG. 2.

FIG. 6 is a cross-sectional view of the fixed beam taken along the line 6-6 of FIG. 3.

FIG. 7 is a cross-sectional view of the dump-book assembly taken along the line 7-7 of FIG. 3.

FIG. 8 is a sectional view of the travelling boom showing the dump-book assembly in side elevation in its inboard position.

FIG. 9 is a sectional view of the travelling boom showing the dump-book assembly in side elevation in its outboard position and rotated to release a capsule.

FIG. 10 is a perspective view of a valley stop.

DESCRIPTION OF THE PREFERRED EMBODIMENT

As shown in FIG. 1, the numeral 10 designates the herein-described gravity davit which is shown supported above a deck, platform or superstructure 12 (generically referred to herein as a "deck" or "decking") by suitable support means such as the support bars 14. Other types of support means may be employed as is well known and they will not be further described as the particular design of the support means does not constitute a part of this invention. The support bars 14 cant or angle the gravity davit 10 with respect to the deck 12 so that it can be extended by gravity as will be described in more detail hereafter. This canting of the gravity davit 10 provides it with a downwardly-extending, outboard end and with an upwardly-extending inboard end.

In FIG. 1, a survival capsule 20 such as is described in U.S. Pat. No. 3,259,926, issued July 12, 1966, is shown suspended from the gravity davit 10 in its inboard (solid outline) and outboard (phantom line) positions. The survival capsule 20 is shown for exemplary purposes only, as it will be appreciated that other life crafts and even bodies not used for life-saving purposes may be suspended from the gravity davit 10.

The gravity davit 10 comprises a fixed hollow beam 22 to which the support rods 14 are connected, a hollow travelling boom 24 which telescopes into and is slidably within the fixed beam 22, a dump-book assembly 26 which is carried within the travelling boom 24 for slidable movement within the latter, and cable and powered winch means for controlling the rate of outboard movement of the capsule 20 and for returning

the capsule to its inboard position. Both the travelling boom 24 and dump-hook assembly 26 have inboard and outboard positions with movement of each between their respective inboard and outboard positions taking place while the other is at rest. In FIG. 2, the travelling boom 24 is shown in its inboard position retracted into the fixed beam 22 with the dump-hook assembly 26 located at its inboard position within the travelling boom 24 directly above the capsule 20. Under the influence of gravity, the travelling boom 24 moves to its outboard position which is shown in phantom outline in FIG. 1 and in solid line in FIG. 3. Also under the influence of gravity, the dump-hook assembly 26 moves to its outboard position within the travelling boom 24 (FIG. 4).

Outboard movement of the capsule 20 is gravity induced with its rate being controlled both by the angle (with respect to the horizontal) of the davit 10 and by brake means, whereas inboard movement of the capsule 20 is governed by separate power means. The latter, as shown in FIG. 1, comprises a motor 28 which may be mounted on the davit 10 (as shown in FIG. 1) or on the deck 12 and which is operably connected to a winch 30. A brake 31 such as that disclosed in U. S. Pat. No. 3,702,690, issued Nov. 14, 1972, may be employed as the brake means to govern the rate of rotation of the winch 30. A cable 32 is attached at one end to the winch 30 and extends through the davit 10 for attachment at its other end to the capsule 20. As the capsule 10 moves outboard under the influence of gravity, a restraining force is applied to it through the cable 32 by the brake 31 acting on the winch 30. To return the capsule 20 to its inboard position, the rotation of the winch 30 is reversed and the motor 28 controls its rotation so that the cable 32 is taken up to thereby return the dump-hook assembly 26 and travelling boom 24 to their respective inboard positions as will be described in more detail hereinafter.

The fixed beam 22 will next be described with particular reference to FIGS. 2-6. This beam 22 is internally provided with an overhead V-rail 34 and an inverted-V, surface rail 36 between and along which the travelling boom 24 runs. The overhead rail 34 depends from the ceiling 38 of the fixed beam 22 and extends more than half-way to the latter's outboard end 40 from adjacent its inboard end 42 preferably symmetrically disposed along the vertical, longitudinal center line of the fixed beam 22. The surface rail 36 extends upwardly from the floor 44 of the fixed beam 22 and is also preferably symmetrically disposed along the vertical center-line of the latter so that it is substantially diametrically opposed to the overhead rail 34. Additionally, the surface rail 36 is substantially co-extensive with the overhead rail 34 except that the surface rail terminates a spaced distance from the inboard end 42 of the fixed beam 22. Between the inboard end of the surface rail 36 and that of the fixed beam 22, the floor 44 of the fixed beam defines a centrally-disposed slot 46 (FIG. 4 and 6). Bearing means 48 are carried within the fixed beam 22 by upturned flanges 50 disposed adjacent this slot 46 so that a sheave 52 which is rotatably supported on the bearing means partially extends through the slot.

Adjacent the outboard end 40 of the fixed beam 22, a pair of roller bearings 54 (FIG. 5) are rotatably mounted in the side walls 56 of the fixed beam to support a pair of rollers 58,60, thereon within the fixed beam. Preferably, the rollers 58,60 include a V-type

roller 58 and a flat roller 60 having side shoulder recesses 61. An elongated slot 62 is formed in the floor 44 of the fixed beam 22 and extends inboard from the outboard end 40 thereof to terminate short of the surface rail 36 to permit extension of the cable 32 and a portion of the dump-hook assembly 26 downwardly therethrough from the inboard position of the dump-hook assembly 26 to the outboard end of the fixed beam 22 so that the capsule 20 remains disposed vertically below the dump-hook assembly 26 at all times.

Still referring to FIG. 2-6, the travelling boom 24 is essentially hollow with its sides defining a pair of opposing, inwardly-facing, guide channels 64 which cooperate to guide the dump-hook assembly 26 along the travelling boom 24. The bottom wall of the travelling boom 24 is provided with a longitudinal slot 65 (FIG. 4) extending from the outboard end 78 of the travelling boom to the inboard position of the dump-hook assembly 26 to permit extension therethrough of the cable 32 and part of the dump-hook assembly.

Means are provided on the travelling boom 24 for rolling engagement with the overhead and surface rails 34, 36 within the fixed beam 22. Such means includes a pair of V-pulleys 66,68 which are rotatably mounted on brackets 70, 72 affixed to the inboard end 74 and to the underside adjacent to the inboard end 74, respectively, of the travelling boom 24 to engage the overhead and surface rails 34,36, respectively, of the fixed beam 22. The travelling boom 24 is also provided with a V-type guide rail 76 depending from the underside of the travelling boom 24 for engagement with the V-roller 58 carried adjacent the outboard end 40 of the fixed beam 22. The guide rail 76 extends from the outboard end 78 of the travelling boom 24 inwardly a distance sufficient to provide engagement of this guide rail 76 with the V-roller 58 over the length of travel of the travelling boom 24. The opposite side of the underside of the travelling boom 24 is provided with a flat surface 79 for rolling engagement with the flat roller 60 which is mounted along side the V-roller 58. The flat surface 79 is substantially co-extensive with the guide rail 76.

In summary, the travelling boom 24 is capable of inboard and outboard movement within the fixed beam 22. When so moving, the travelling boom 24 is supported by the V- and flat rollers 58,60 mounted adjacent the outboard end 40 of the fixed beam and by the pulley 68 mounted underneath the travelling boom 24 adjacent its inboard end 74. As the travelling boom 24 moves towards its outboard position (FIG. 3), its inboard end section exerts an increasing force upwardly against the ceiling 38 of the fixed beam 22. Friction produced by this force is minimized due to the rolling action of the pulley 66 as it moves along the overhead rail 34 depending from the fixed beam ceiling 38.

Inboard movement of the travelling boom 24 preferably stops when it is substantially telescoped into the fixed beam 22 to provide the most compact package to thereby minimize the space occupied by the gravity davit 10 when not in use. Such inboard movement of the travelling boom 24 may be controlled by contact of the latter with a limit switch (not shown) which functions to cut off power to the winch 30. A dead-man brake (not shown) is applied at this point to prevent rotational movement of the winch 30 and, thus, outboard movement of the travelling boom 24 until the dead-man brake is released.

Outboard movement of the travelling boom 24 is also limited. A stop block 82 is attached to the topside surface of the travelling boom 24 a spaced distance from its inboard end 74 so that the travelling boom 24 reaches its outboard position (FIG. 3), the stop block 82 abuts against another stop block 84 which depends from the ceiling 38 of the fixed beam 22. Additionally, a pair of valley stops 85 are positioned in the bottom of the travelling boom 24 adjacent to the inboard ends of each of the flat surface 80 and guide rail 76 on the underside of the travelling boom. The valley stops 85 may be constructed as shown in FIG. 10 and all valley stops may or may not be the same. Referring to FIG. 10, the valley stop 85 comprises a block 86 which has a face 87 which is laterally defined by walls 88 which project from the block. Transverse, aligned grooves 89,91 are formed in the walls 88 and block surface 87, respectively, to receive the V- and flat rollers, 58,60. When the travelling boom 24 travels outward, the flat and V-rollers 60,58, in effect, travel to the inboard ends of the flat surface 80 and guide rail 76, respectively, where they then drop into the valley stops 85 where they remain until the travelling boom 24 is retracted into the fixed beam 22.

Turning now to the dump-hook assembly 26, the latter is shown in its inboard position (with respect to the travelling boom 24) in both FIG. 2 and 3 and in its outboard position in FIG. 4. With particular reference to FIG. 7-9, the dump-hook assembly 26 comprises a pair of hook plates 90 which, in turn, comprise upper and lower jaw sections 92,94, respectively, defining a mouth 95. The hook plates 90 are spaced apart from each other by spacers 96 welded thereto. Each upper jaw section 92 has a normally inboard extension 98 to which a pin 100 is welded for rotatably mounting a roller 102 external to the hook plates 90 so that they are spaced apart and sized to be received by the guide channels 64 formed internally of the travelling boom 24. A sheave 104 is rotatably mounted between the hook plates 90 out-board of the rollers 102 on the upper jaw section 92 on a pin 106 extending between and through the hook plates. The cable 32 extends over the sheave 104. A second pair of rollers 107 are rotatably carried on the pin 106 external to the hook plates 90 for reception by the travelling boom opposing guide channels 64. Normally, the extension 98 of the upper jaw section 92 is tilted inboard with respect to that portion of the upper jaw section which carries the sheave 104 so that the mouth 95 is tilted with its open end up.

The dump-hook assembly 26 is maintained in its inboard position by a latch mechanism 108 (FIG. 2-4 and 8) which is hydraulically operated. The latch mechanism 108 comprises a bell crank 110 which is pivotally mounted at its apex to a supporting bracket 112 by a pivot pin 114 extending therethrough. The supporting bracket 112, in turn, is affixed to a base plate 116 on the bottom of, and within, the travelling boom 24. An inboard arm 117 of the bell crank 110 is pivotally connected to a piston 118 which extends into one end of a hydraulic cylinder 120 which is anchored at its other end to the base plate 116 and which is operably connected through hydraulic fluid lines 122, 123 to a contact-actuated, valve release trigger 124 (FIG. 2 and 3) mounted on the underside of the travelling boom 24. The outboard arm 126 of the bell crank 110 has a groove 128 formed in its inner side to receive a

locking pin 130 extending between, and connected to, the hook plates 90.

When the dump-hook assembly 26 is in its inboard position with respect to the travelling boom 24, an hydraulic valve is closed so that the piston 118 is in its retracted position in the hydraulic cylinder 120. This forces the bell crank 110 to pivot about the base pivot pin 114 so that the outboard arm 126 is elevated as shown in solid line in FIG. 8 to thereby retain the locking pins 130 in the groove 128 in the outboard arm so that the dump-hook assembly 26 is prevented from moving outboard from its inboard position.

As the travelling boom 24 travels in an outboard direction from its inboard position, as previously described, the dump-hook assembly 26 is carried therein in its inboard position. When the travelling boom 24 has reached its outboard position, the dump-hook assembly 26 is then released for its outboard travel. At the same time that the stops 84,82 on the fixed beam 22 and travelling boom 24, respectively, abut one another to stop the outboard movement of the travelling boom and the V- and flat rollers 58,60 drop into the valley stops 85, the valve release trigger 124 is depressed by contact with a stop 140 extending upwardly from the floor 44 of the fixed beam 22. Such contact allows release of hydraulic fluid from the cylinder 120 through line 123 so that the downward load acting through the bell crank 110 on the piston 118 will extend the piston 118 to permit counterclockwise pivotal movement (as seen in FIG. 8) of the bell crank 110 about its base pivot pin 114 to, in turn, permit the outboard arm 126 of the bell crank to tilt downwardly (as shown in dashed outline in FIG. 8) so that the locking pin 130 is pulled out of its retaining groove 128 by the weight of the dump-hook assembly 26 acting under the influence of gravity. The bell crank 110 immediately returns under the influence of an internal cylinder spring (not shown). The dump-hook assembly 26 is then free to move toward its outboard position under the continuing influence of gravity, but subject to restraint by a governor brake acting against the winch 30 with the restraining force being transmitted to the dump-hook assembly 26 through the cable 32.

Outboard movement of the dump-hook assembly 26 is limited by abutment of the outboard rollers 107 against stop blocks 142 attached to the inner sides of the travelling boom 24. At the same time, the outboard rollers 107 of the dump-hook assembly 26 drop into valley stops 144 (FIG. 2 and 3) similar to those designated by the numeral 85 so that the dump-hook assembly cannot prematurely return.

To permit the capsule 20 to be lowered, the dump-hook assembly 26 is permitted to rotate about the axis of the sheave 104 until the mouth 95 of the dump-hook assembly is tilted downward to permit release of a bobbin-like fitting 146 swaged to the cable 32 from the jaws 92,94 of the dump-hook assembly 26. This is shown by a comparison of FIG. 8 and 9. This is accomplished by providing a cut-out 148 in the top of the travelling boom 24 so that the inboard extension 98 of the upper jaw section 92 together with the rollers 102 carried thereon are free to rotate upwardly through the cut-out 148 about the sheave 104 axis when the outboard rollers 107 drop into the valley stops 104. This rotational movement of the inboard extension 98 is limited by its abutment with a limit pin 150 affixed to the travelling boom 24 outboard of the cut-out 148. Abut-

ment of the inboard extension 98 with the rotational limit pin 150 occurs after the jaws 92,94 have been sufficiently tilted to permit escape of the cable fitting 146 from the mouth 95 of the dump-hook assembly 26. As the dump-hook assembly 26 rotates, the cable 32 is able, in effect, to pass between the hook plates 90 and the rollers 102 because the pins 100 on which the rollers 102 are mounted do not interconnect the hook plates so that a passageway is left therebetween in the region of the inboard extension 98.

To retrieve and stow the capsule 20, the winch 30 is reversed as power is applied thereto by the motor 28 to wind in the cable 32. As the capsule 20 is raised, the cable fitting 146 comes in contact with the lower edge of the upper jaw section 92 of the dump-hook assembly 26. The cable fitting 146 is urged into the mouth 95 of the dump-hook assembly 26 which simultaneously commences to rotate clockwise (as viewed in FIG. 9) about the sheave 104 axis. Movement of the cable fitting 146 into the mouth 95 and rotation of the dump-hook assembly 26 are both facilitated by the eccentric position of the cable fitting with respect to the axis of rotation through the sheave 104 which thereby produces a torque on the dump-hook assembly 26 causing it to rotate clockwise (as viewed in FIG. 9) and by the curvature given to the lower edge of the upper jaw section 92. Rotation of the dump-hook assembly 26 continues until the inboard rollers 102 are returned to the guide channels 64 in the travelling boom 24. Then, and not before, the force transmitted through the cable 32 from the motor 28 to the dump-hook assembly 26 is sufficient (in the absence of dump-hook assembly rotation) to pull the latter out of its valley stops 144 to start it on its inboard journey along the travelling boom 24.

As the dump-hook assembly 26 approaches its inboard position, the locking pin 130 depresses the outboard arm 126 of the bell crank 110 to be received by the groove 128. Substantially simultaneously therewith, the inboard rollers 102 contact another pair of stops 152 attached to the inner sides of the travelling boom 24 causing the latter to begin its inboard journey into the fixed beam 22 as force continues to be exerted on the dump-hook assembly 26 through the cable 32. As the travelling boom 24 begins its inboard journey, the valve release trigger 124 moves inboard out of contact with the fixed beam stop 140. This causes the piston 118 to be retracted into the hydraulic cylinder 120 which causes pivotal movement of the bell crank 110 to retain the locking pin 130 in the bell crank groove 128.

As the dump-hook assembly 26 reaches its maximum inboard position within the travelling boom 24, it causes the travelling boom 24 to move inboard lifting the travelling boom valley stops from the fixed beam rollers 58,60 and the travelling boom telescopes into the fixed beam 22 until it, too, reaches its inboard position at which time power to the winch 30 is cut off as previously described. Conventional brake systems may be employed to ensure that the gravity davit 10 remains stowed.

We claim:

1. A telescoping gravity davit, comprising a hollow fixed beam having first and second ends and defining an elongated slot extending from said first end toward said second end in the bottom thereof, a hollow travelling boom slidably receivable by said fixed beam and having first and second ends and

defining an elongated slot extending from said first ends towards said second end in the bottom thereof in juxtaposed, aligned relation with said slot in said fixed beam;

first limit means attached to said fixed beam and to said travelling boom for limiting further movement of said travelling boom relative to said fixed beam after said travelling boom has been substantially extended from said fixed beam;

a dump-hook assembly slidably carried within said travelling boom for travel therealong towards said first end of said travelling boom from a stowed position within said travelling boom for suspending a body therebelow from a cable extending through said aligned slots and over said dump-hook assembly;

releasable locking means positioned within said travelling boom intermediate the ends thereof for locking said dump-hook assembly in said stowed position intermediate said ends of said travelling boom and for releasing said assembly in an outboard direction;

actuation means connected to said locking means and positioned on said fixed beam and said travelling boom to (1) actuate said locking means to release said dump-hook assembly therefrom for movement toward said first end of said travelling boom at substantially the same time as said first limit means acts to stop movement of said travelling boom outward of said fixed beam and to (2) actuate said locking means to lock said dump-hook assembly in said stowed position at substantially the same time as said dump-hook assembly returns to said stowed position; and

second limit means positioned on said travelling boom adjacent its first end for engagement with said dumphook assembly to limit movement of said dump-hook assembly toward said first end of said travelling boom.

2. The davit of claim 1 including:

stop means positioned within said travelling boom for engagement with said dump-hook assembly at substantially the same time as said dump-hook assembly re-engages said locking means to permit commencement of movement of said travelling boom into said fixed beam at substantially the same time as said dump-hook assembly returns to said stowed position.

3. The davit of claim 1, further including rotation means carried on said travelling boom adjacent said first end thereof for rotating said dump-hook assembly to release said body therefrom when said dump-hook assembly engages said second limit means.

4. The davit of claim 1 wherein said actuation means comprises:

contact means positioned within said fixed beam; and trigger means operably connected to said locking means and carried on said travelling boom in a position such that (1) said trigger means contacts said contact means on said fixed beam at substantially the same time as said first limit means acts to stop movement of said travelling boom outward of said fixed beam and (2) said trigger means moves out of contact with said contact means at substantially the same time as said dump-hook assembly re-engages said locking means.

5. A telescoping gravity davit, comprising:
 a hollow fixed beam having a first and a second end and defining an elongated slot extending from said first end toward said second end in the bottom thereof; 5
 a hollow travelling boom slidably receivable by said fixed beam and having first and second ends and defining an elongated slot extending from said first end toward said second end in the bottom thereof in juxtaposed alignment with said slot in said fixed beam; 10
 first stop means attached to said fixed beam intermediate the ends thereof; 15
 second stop means attached to said travelling boom intermediate the ends thereof for engagement with said first stop means to limit movement of said travelling boom out of said fixed beam after said travelling boom has been substantially extended from said fixed beam; 20
 a dump-hook assembly slidably carried within said travelling boom for travel therealong towards said first end of said travelling boom from a stowed position intermediate said ends of said travelling boom, said dump-hook assembly suspending a body therebelow on a cable extending through said aligned slots and over said dump-hook assembly; 25
 releasable locking means positioned within said travelling boom for locking said dump-hook assembly in said stowed position; 30
 contact means positioned within said fixed beam; trigger means operably connected to said locking means to actuate said locking means to alternately release and lock said dump-hook assembly from and into, respectively, said locking means, and positioned on said travelling boom (1) so that it contacts said contact means on said fixed beam at substantially the same time as said second stop means on said travelling boom engages said first stop means on said fixed beam to release said dump-hook assembly for movement along said travelling boom toward said first end thereof at substantially the same time as said travelling boom stops its outward travel relative to said fixed beam and (2) so that it moves out of contact with said contact means at substantially the same time as said dump-hook assembly re-engages said locking means to lock said dump-hook assembly in said stowed position; 45
 third stop means positioned within said travelling boom for engagement with said dump-hook assembly when said dump-hook assembly re-engages said locking means; and 50
 fourth stop means positioned within said travelling boom adjacent its first end to limit movement of said dump-hook assembly toward said first end. 55

6. The davit of claim 5 wherein:
 said travelling boom defines a pair of inwardly-facing, opposing guide channels extending from adjacent said first end to at least adjacent said locking means and further defines a cut-out adjacent said first end to provide vertical communication of said guide channels with the exterior of said travelling boom through the top thereof; and 60
 said dump-hook assembly includes first and second roller means receivable by said travelling boom guide channels for guiding said dump-hook assembly therealong, said first roller means being posi- 65

tioned closest to said first end of said travelling boom and said second roller means being spaced therefrom so that said second roller means rotates out of said guide channels through said cut-out when said dump-hook assembly engages said fourth stop means and rotates about a transverse axis through said first roller means under the influence of the weight of said body. 7. The davit of claim 6 which further includes: first valley stop means disposed within said travelling boom adjacent said first end and sized to partially receive said first roller means of said dump-hook assembly substantially at the same time as said dump-hook assembly engages said fourth stop means adjacent said first end of said travelling boom. 8. The davit of claim 7 which further includes: third roller means rotatable carried within said fixed beam adjacent an end thereof through which said travelling boom projects; and second valley stop means disposed under said travelling boom intermediate said first and second ends to partially receive said third roller means, said second valley stop means being positioned so that said second valley stop means receives said third roller means at substantially the same time as said trigger means contacts said contact means and said first and second stop means abut each other. 9. The davit of claim 6 wherein said dump-hook assembly further includes:
 a pair of spaced plates defining a pair of aligned, generally horizontal slots which form a mouth opening toward said first end of said travelling boom, said first and said second roller means being rotatably mounted on outwardly-facing sides of said spaced plates; and
 a sheave rotatably carried by and between said first and second plates between said first roller means. 10. The gravity davit of claim 5 which further includes:
 means for supporting said gravity davit above a deck at an angle relative thereto with said first end of said fixed beam projecting downwardly so that said travelling boom and said dump-hook assembly are free to roll along said fixed beam and said travelling boom, respectively, under the influence of gravity; said cable extending through said fixed beam and said travelling boom and over said dump-hook assembly to attach at one end to said body suspended below said dump-hook assembly and at its other end to a winch; 45
 brake means associated with said winch for controlling the rate of gravitationally-induced movement of said travelling boom and said dump-hook assembly; and
 power means connected to said winch for retracting said travelling boom into said fixed beam and for returning said dump-hook assembly to said stowed position. 11. A telescoping gravity davit comprising:
 a hollow fixed beam having an inboard and an outboard end and defining an axially-aligned, elongated slot extending from said outboard end a substantial distance toward said inboard end along the bottom of said fixed beam; 50
 a hollow, travelling boom sized to telescope into said fixed beam and having an inboard end and an out- 55

board end and defining an axially-aligned, elongated slot in its bottom wall vertically spaced above said elongated slot in said fixed beam and extending from said outboard end a substantial distance toward said inboard end, said travelling boom further defining a pair of inwardly-facing, opposing guide channels extending from said outboard end a substantial distance toward said inboard end, said guide channels communicating with the exterior of said travelling boom through a cut-out in the top 10 thereof adjacent said outboard end;

first movement means carried on said travelling boom;

second movement means disposed within said fixed beam for cooperation with said first movement means to provide rolling movement of said travelling boom with respect to said fixed beam when said fixed beam is tilted with respect to the horizontal; 15

first stop means disposed within said fixed beam; 20

second stop means carried on said travelling boom for engagement with said first stop means to limit outboard-directed movement of said travelling boom relative to said fixed beam;

a dump-hook assembly disposed within said travelling boom for movement relative thereto between an outboard position adjacent said outboard end of said travelling boom and an inboard position intermediate said ends of said travelling boom, said elongated slots and said opposing guide channels 25 extending inboard to said inboard position of said dump-hook assembly when said travelling boom is substantially telescoped into said fixed beam, said dump-hook assembly comprising,

a pair of vertically-aligned, spaced plates defining 30 a pair of aligned, generally horizontal slots forming a mouth opening toward said outboard end of said travelling boom,

first and second roller means rotatably mounted on 35 outwardly-facing sides of said spaced plates and sized to be received by said guide channels in said travelling boom for guiding said dump-hook assembly therealong, said first roller means being positioned closest to said outboard end of said travelling boom and said second roller means being spaced therefrom so that said second roller means rotates out of said guide channels through 40 said cut-out when said dump-hook assembly is rotated about a transverse axis through said first roller means, and

a sheave rotatably carried between said plates between said first roller means for guiding a cable thereover; 45

locking means disposed within said travelling boom for locking said dump-hook assembly in said inboard position; 50

contact means positioned within said fixed beam; 55

trigger means operably connected to said locking means and positioned on said travelling boom (1) so that it contacts said contact means on said fixed beam at substantially the same time as said second stop means on said travelling boom engages said first stop means on said fixed beam to release said dump-hook assembly from said locking means for movement along said travelling boom toward said outboard end thereof at substantially the same time as said travelling boom stops its outboard-directed 60

65

travel relative to said fixed beam and (2) so that it moves out of contact with said contact means at substantially the same time as said dump-hook assembly re-engages said locking means;

third stop means positioned within said travelling boom for engagement with said dump-hook assembly when said dump-hook assembly re-engages said locking means at its inboard position to limit inboard-directed movement of said dump-hook assembly;

fourth stop means carried within said travelling boom adjacent its said outboard end for limiting outboard-directed movement of said dump-hook assembly, said fourth stop means being positioned outboard of said cut-out a spaced distance to permit rotation of said second roller means out of said guide channels when said outboard-directed movement of said dump-hook assembly stops;

first valley stop means positioned within said guide channels of said travelling boom adjacent its outboard end and sized to partially receive said first roller means at substantially the same time as said dump-hook assembly contacts said fourth stop means;

second valley stop means carried on the underside of said travelling boom and engageable with said second movement means at substantially the same time as said first and second stop means engage each other.

12. The gravity davit of claim 11 wherein:

said first movement means comprises,

a first pulley carried on and extending above said travelling boom adjacent its inboard end,

a second pulley attached to and depending from said travelling boom adjacent its inboard end, and

track means on the undersurface of said travelling boom extending from adjacent its outboard end towards its inboard end; and

said second movement means comprises,

a first rail attachment to and depending from the roof of said fixed beam and extending from adjacent its inboard end towards its outboard end for engagement with said first pulley,

a second rail attached to and extending upwardly from the floor of said fixed beam and extending from adjacent its inboard end towards its outboard end for engagement with said second pulley, and

roller means disposed within said fixed beam adjacent its outboard end and extending upwardly from said floor of said fixed beam for engagement with said track means on said travelling boom, said roller means being partially receivable by said second valley stop means.

13. The gravity davit of claim 11 which further includes:

means for supporting said gravity davit above a deck at an angle relative thereto with said outboard end of said travelling boom projecting downwardly so that said travelling boom and said dump-hook assembly are free to roll along said fixed beam and said travelling boom, respectively, under the influence of gravity;

said cable extending through said fixed beam and said travelling boom and over said dump-hook assembly sheave to attach at one end to a body sus-

13

pended below said dump-hook assembly and at its other end to a winch;
brake means associated with said winch for controlling the rate of outboard-directed movement of said travelling boom and said dump-hook assem- 5

14

bly; and
power means connected to said winch for drawing said travelling boom and said dump-hook assembly inboard.
